UNITED STATES PATENT OFFICE.

ARTHUR G. WARREN, OF WORCESTER, MASSACHUSETTS.

DESIGN FOR AN EMBLEMATIC BADGE, PIN, OR BUTTON.

59,796.

Specification for Design.

Patented Nov. 22, 1921.

Application filed December 23, 1920. Serial No. 432,877. Term of patent 14 years.

To all whom it may concern:

Be it known that I, ARTHUR G. WARREN, ton, showing my new design, a citizen of the United States, residing in Worcester, in the county of Worcester and State of Massachusetts, have invented a new, original, and ornamental Design for an Emblematic Badge, Pin, or Button, of which the following is a specification, reference being had to the accompanying drawing, forming part thereof.

The figure is a plan of an emblematic button, showing my new design.

I claim:—

The ornamental design for an emblematic badge, pin, or button, or article of a similar nature, as shown.

ARTHUR G. WARREN.
